SQUARE STERNED CANOE

Robert M. Taft, 10344 Mississippi Drive, Coon Rapids, Minn., and John Sawicki, Minneapolis, Minn., assignors of one-half to said Robert M. Taft, Coon Rapids, Minn., and one-half to Warren R. Taft, South Haven, Minn.

Filed Nov. 2, 1960, Ser. No. 62,708

Term of patent 14 years

(Cl. D71—1)

We claim:

The ornamental design for a square sternen canoe, substantially as shown.
